UNITED STATES PATENT OFFICE.

FRANK R. PIPER, OF CANTON, OHIO.

ADDING MACHINE.

No. 895,678.

Specification of Letters Patent.

Patented Aug. 11, 1908.

Application filed March 20, 1908. Serial No. 422,265.

To all whom it may concern:

Be it known that I, FRANK R. PIPER, a citizen of the United States, residing at Canton, in the county of Stark and State of Ohio, have invented a new and useful Improvement in Adding-Machines, of which the following is a specification.

The invention relates to a device for mechanically adding two or more numbers by means of a series of rotatable coördinated disks; and the objects of the invention are to provide means for coöordinating the movement of one disk with another, and for returning all the disks to a zero position by a single and simple operation. These objects are attained by the construction, mechanism and arrangement illustrated in the accompanying drawings, in which—

Figure 1 is a plan view of the adding machine showing some parts broken away to disclose details of the mechanism; Fig. 2, a transverse section on the axis of one disk; Fig. 3, a detached perspective view of the coöordinating mechanism; Fig. 4, a detached perspective under side view of the ratchet wheel; and Fig. 5, a detached perspective view of one resetting pinion.

Similar numerals refer to similar parts throughout the drawings.

The case of the machine is preferably made of the body 1 and the cover 2; and for convenience the body is preferably pressed or shaped out of sheet metal to form the bottom and sides of the case, with the peripheral flanges 3, over which the edges of the cover are adapted to be turned and fastened. The series of pivot posts 4 are securely fastened, as by riveting or otherwise, to the bottom of the case, and on the upper end thereof, immediately underneath the cover, are rotatably mounted the series of numeral disks 5, which disks are provided with the holes or indentures 6 annularly located on the face thereof and correspond in number with the system of numerals employed, which in the present instance is the decimal system, as distinguished by Arabic figures, which figures are indicated on the face of the disk, one being located outside of each indentation.

In the cover of the case are provided a series of round openings, registering with the respective disks and adapted to expose the annular row of indentations therein but covering the figures thereon. The sight apertures 7 are also provided in the cover of the case, adjacent to the disk openings, and pref-

erably located on the upper side of the same as the machine is viewed by the operator, and these apertures are adapted to expose, one at a time, the respective figures on the disk. Around the disk openings of the case are indicated the same series of figures shown on the disks, and the stop shoulder 8 is provided on the cover in the disk opening, so that the disks are adapted to be manipulated by a pencil point, stylus, or other tool, in the manner usually employed in machines of this character. The ratchet wheels 9 are rotatably mounted on the pivot posts and are formed on or fastened to the numeral disks with which they are adapted to rotate.

The coöordinating mechanisms are each composed of the swinging frame 10 pivoted on the ends of the links 11 which in turn are pivoted to the case, preferably to the bottom near one side thereof. At one end of the swinging frame is formed or attached the arm 12, the end of which is located in the path of the lug 13 formed or attached on the side of the adjacent ratchet wheel, by means of which the frame is adapted to be swung by the lug when the ratchet is rotated in the forward direction, as indicated by arrows in the drawings; and the spring detent 14 is formed or fastened on the other end of the swinging frame, and is adapted to engage with the teeth of the next adjoining ratchet wheel, and to communicate to the same the movement of the swinging frame. The spring 15, extending between the fixed pivot of one link and the swinging pivot of the opposite link, is adapted to return and hold the swinging frame to its normal position against the stop post 16 which is fastened to the bottom of the case.

The spring stop detents 17 are fastened to the bottom of the case, one at the side of each ratchet wheel, and these detents are adapted to stop the ratchet wheels against a reverse or backward rotation. It will be understood that the number of teeth in each ratchet wheel corresponds with the number of numerals or figures employed on the respective disks according to the system of enumeration which is used, and that the swinging frame is adapted to rotate one disk the distance of one tooth for each part or complete rotation of the actuating disk, as usually required in machines of this type.

The resetting pinions 18 are rotatably mounted on the pivot posts, and are free to slide endwise thereon. The ends of the pin-

ions are normally held against the hubs 19 of the ratchet wheels by means of the coil-springs 20 located around the pivot posts between the pinions and the bottom of the case, in the latter of which the springs are 5 preferably slightly countersunk, as shown. The end of each ratchet wheel hub is notched or inclined at one side to form the shoulder 21 in which notch and against which shoulder 10 the tongue 22 formed or attached on the adjacent end of the pinion is adapted to operate. The rack-bar 23 is mounted endwise in the case and adapted to mesh with each one of the resetting pinions. The rack-bar is 15 adapted to be moved endwise, by sliding in the bearings 24 provided in the end walls of the case, and is normally held in its inoperative position by a spring, as the coil-spring 20 is located around the bar between one end of 20 the case and the stop shoulder 25 on the bar. The other end of the bar is arranged to project from the end of the case and is preferably provided with the thumb button 26, and it is evident that by pressing against this end 25 of the bar, the same will slide endwise against the action of the spring and will rotate all the resetting pinions in unison.

The parts are so arranged that when any one numeral disk is rotated forward, the 30 tongue on the end of the resetting pinion will slide and ride out of the inclined notch and on the end of the hub of the ratchet wheel, in doing which the coil-spring which acts to hold the pinion against the hub, is compressed and the hub is moved endwise along the pivot post away from the hub, the hub being held against rotation by its engagement with the rack bar; and that when the 35 resetting pinions are all rotated in unison by an endwise movement of the rack bar, the pinion tongues will engage in the notches against the shoulders on the hub of the ratchet wheels, and will rotate each wheel forward to its zero position, by means of 40 which all the numeral disks are reset in unison to the proper position for adding a new series of numbers.

The longitudinal slots 27 are preferably provided in the rack-bar, and are adapted to 45 operate on the pins or posts 28, thus holding the rack-bar in mesh with the respective pinions throughout its length; and it will be understood that when this form of guides is employed, the operation of the end bar 50 through the bearing 24 in the end of the case is neither essential nor necessary. It will also be understood that it is not essential to use the springs 20 for the purpose of holding the pinions up against the hubs of the 55 ratchet wheels, and when this spring is not employed, the weight of the ratchet wheels and the superimposed disks can be depended upon for this purpose, in which event the disks and wheels are together arranged to 60 slide endwise on the pivot posts.

What I claim as my invention, and desire to secure by Letters Patent, is—

1. In an adding machine having a case with a series of pivot posts therein, a series of numeral disks and ratchet wheels rotatably mounted on the posts and automatic detents in the case adapted to stop the ratchet wheels against backward rotation; a disk-coördinating mechanism comprising links pivoted at one end to the case, a spring-controlled frame pivoted to the other ends of the links, a spring-controlled detent on the frame adapted to operate on the teeth of one ratchet wheel to rotate it forward, and a lug on an adjacent ratchet wheel adapted to about 70 and swing the frame during a certain portion of the rotation of the adjacent wheel.

2. In an adding machine having a case with a series of pivot posts therein, a series of numeral disks and ratchet wheels rotatably mounted on the posts and automatic detents in the case adapted to stop the ratchet wheels against backward rotation; a disk-resetting mechanism comprising a series of endwise-slidable rotatable pinions on the pivot posts having tongues on the ends thereof, inclined notches with shoulders in the adjoining portions of the ratchet wheels adapted to receive and engage the tongues, springs acting to hold the pinions against 80 the ratchet wheels, and an endwise-slidable spring-controlled rack-bar in the case adapted to rotate the pinions in unison.

3. In an adding machine having a case with a series of pivot posts therein, a series of numeral disks and ratchet wheels rotatably mounted on the posts and automatic detents in the case adapted to stop the ratchet wheels against backward rotation; a disk-resetting mechanism comprising a series of endwise-slidable rotatable pinions on the pivot posts having tongues on the ends thereof, inclined notches with shoulders in the adjoining portions of the ratchet wheels adapted to receive and engage the tongues, springs acting to hold the pinions against 90 the ratchet wheels, and an endwise-slidable rack-bar in the case adapted to rotate the pinions in unison.

4. In an adding machine having a case with a series of pivot posts therein, a series of numeral disks and ratchet wheels rotatably mounted on the posts and automatic detents in the case adapted to stop the ratchet wheels against backward rotation; a disk-resetting mechanism comprising a series of rotatable pinions on the pivot posts having tongues on the ends thereof, inclined notches with shoulders in the adjoining portions of the ratchet wheels adapted to receive and engage the tongues, and an endwise-slidable rack-bar in the case adapted to rotate the pinions in unison.

5. In an adding machine having a case with a series of pivot posts therein, a series

of numeral disks and ratchet wheels rotatably mounted on the posts and automatic detents in the case adapted to stop the ratchet wheels against backward rotation; a disk-resetting mechanism comprising a series of pinions adapted to be rotated in unison on the pivot posts and having tongues on the ends

thereon and inclined notches with shoulders in the adjoining portions of the ratchet wheels adapted to receive and engage the tongues. 10
